6 Claims. (Cl. 164—281)

The invention relates to an induction furnace for horizontal, continuous metal casting, having an outlet in the lower portion of the furnace for releasing the melt.

In conventional induction furnaces of the aforesaid type the current in the melt produced by the electric field causes difficulties when casting because this current disturbs flow of the melt into the mold whereby the quality of the cast metal is impaired.

It is the object of the invention to provide an induction furnace for horizontal, continuous metal casting which avoids the difficulties experienced with conventional induction furnaces, by providing a hollow body at the outlet of the furnace which body extends into and communicates the interior of the furnace to the mold. The hollow body extending into the furnace intercepts the current in the melt caused by the electric field and effects calming of the metal flowing through the hollow body before the metal reaches the mold. There are therefore no eddy currents in the melt before entering the mold which facilitates casting and improves the product.

The novel features which are considered characteristic of the invention are set forth with particularity in the appended claims. The invention itself, however, and additional objects and advantages thereof will best be understood from the following description of embodiments thereof when read in connection with the accompanying drawing, the one figure of which shows a longitudinal section through the lower part of a furnace according to the invention.

Referring more particularly to the drawing, numeral 1 designates an induction furnace having an outlet opening 4 in the outer wall 2 close to the bottom 3 of the furnace for releasing the melt, a mold 5 being inserted from the outside into the opening 4. The mold 5 is replaceably connected to the wall 2 and is surrounded by a conventional cooler 6. The furnace 1 has an inner wall 7 which extends around a vertical axis 8 and confines a space 9 which contains induction coils arranged in the conventional manner and not shown. An annular space 10 is formed between the inner wall 7 and the outer wall 2 of the furnace which space is entirely or only partly filled with melt during operation of the furnace.

A hollow body 11 is connected to the furnace wall 2 at the outlet opening 4 and extends into the space 10 containing melt, for conducting melt to the mold 5 connected to the outlet opening 4. The hollow body 11 is made of refractory material and has a configuration similar to that of a quarter bend. The body 11 has an inlet opening 12 placed in a horizontal plane at an elevation somewhat higher than the upper part of the outlet opening 4. The area of the inlet opening 12, which may be round or oval, is smaller than that of the outlet opening of the hollow body and the flow area of the conduit formed by the hollow body increases gradually from the inlet opening to the outlet opening of the hollow body 11.

Before casting, the space 10 in the furnace 1 is filled with liquid metal to above the inlet opening 12 wherefrom the metal flows through the hollow body 11 into the mold 5 where the metal solidifies with the aid of the cooler 6. The solid metal is gradually pulled out of the mold by conventional means, not shown. The hollow body

11 intercepts in the neighborhood of the outlet opening 4 the current of the melt produced by the electric field of the induction coils so that this current cannot adversely affect the metal flowing into the mold 5. The metal flowing into the mold has been calmed in the hollow body 11 so that the horizontal casting process can be operated without disturbance and a homogenous product can be obtained.

The hollow body 11 assures efficient warming up and keeping warm of the mold prior to casting and during casting intermissions because the hollow body 11 is always surrounded during these times by liquid metal remaining in the lower portion of the furnace.

Without departing from the scope of the present invention the outlet opening 4 may be so designed that a plurality of molds can be connected and a plurality of metal bars can be cast simultaneously.

I claim:

1. An induction furnace for horizontal, continuous casting of metal, comprising:

a lower furnace portion,
an outlet opening for the molten metal in said lower furnace portion,
a mold connected to said lower furnace portion within said outlet opening and extending therefrom, and
a hollow body connected to said lower furnace portion at said outlet opening and extending into the furnace for conducting liquid metal from the furnace into said mold, said hollow body having an inlet opening placed inside said lower portion at an elevation above said outlet opening whereby said hollow body interrupts the current within the molten metal to calm the metal flowing through said hollow body.

2. An induction furnace as defined in claim 1 wherein said lower furnace portion has a side wall and a bottom, said outlet opening being in said side wall adjacent said bottom.

3. An induction furnace as defined in claim 1 wherein said hollow body has substantially the configuration of a quarter bend.

4. An induction furnace as defined in claim 1 wherein said hollow body has an inlet opening placed in a horizontal plane.

5. An induction furnace for horizontal continuous casting of metal comprising

a lower furnace portion including a vertical side wall having an outlet opening therein for passage of molten metal through said vertical wall,
a mold connected to said vertical wall within said outlet opening and extending therefrom, and
a hollow body connected to said vertical wall at said outlet opening and extending into said lower surface portion, said hollow body having an inlet opening inside said lower furnace portion above said outlet opening in said vertical wall.

6. An induction furnace as defined in claim 1 wherein said hollow body has an outlet for releasing liquid metal into said mold, the flow area of said hollow body increasing gradually from said inlet opening to said outlet.
